(57) **CLAIM**

The ornamental design for a multi-compartment storage tray for a refrigerator, as shown and described.

DESCRIPTION

FIG. 1 is a left-side, front, top perspective view of a multi-compartment storage tray for a refrigerator, showing my new design;

FIG. 2 is a front elevational view thereof;

FIG. 3 is a top plan view thereof;

FIG. 4 is a right-side elevational view thereof; and,

FIG. 5 is a left-side elevational view thereof.

The broken lines shown in FIGS. 1, 4 and 5 are for illustrative purposes only and form no part of the claimed design.
